DESIGN FOR A COMBINED BOTTLE AND CAP

Benjamin Harris, Los Angeles, Calif.

Application July 10, 1943, Serial No. 110,645

Term of patent 14 years

(Cl. D58—8)

To all whom it may concern:

Be it known that I, Benjamin Harris, a citizen of the United States, residing at Los Angeles, in the county of Los Angeles, in the State of California, have invented a new, original, and ornamental Design for Combined Bottle and Cap, of which the following is a specification, reference being had to the accompanying drawing, forming a part thereof.

In the drawing:

Fig. 1 is an elevational view of a combined bottle and cap showing my new design,

Fig. 2 is a perspective view of the bottle and cap separated,

Fig. 3 is a perspective view of the combined bottle and cap,

Fig. 4 is a top plan view of the combined bottle and cap.

I claim:

The ornamental design for a combined bottle and cap, as shown.

BENJAMIN HARRIS.
